(57) **CLAIM**

The ornamental design for a display screen with graphical user interface, as shown and described.

DESCRIPTION

FIG. 1 is a front elevational view of a first image of a display screen with graphical user interface showing my new design;

FIG. 2 is a front elevational view of a second image thereof;

FIG. 3 is a front elevational view of a third image thereof;

FIG. 4 is a front elevational view of a fourth image thereof;

FIG. 5 is a front elevational view of a fifth image thereof;

FIG. 6 is a front elevational view of a sixth image thereof;

FIG. 7 is a front elevational view of a seventh image thereof; and,

FIG. 8 is a front elevational view of an eighth image thereof.

The appearance of the transitional image sequentially transitions between the images shown in FIGS. 1-8. The process or period in which one image transitions to another image form no part of the claimed design. The broken lines in the drawings depict portions of the display screen with graphical user interface that form no part of the claimed design.
